UNITED STATES PATENT OFFICE.

KARL WIESER, OF RÜTTENSCHEID, NEAR ESSEN-ON-THE-RUHR, GERMANY,
ASSIGNOR TO FRIED. KRUPP, OF ESSEN-ON-THE-RUHR, GERMANY.

PROTECTING-CAP FOR FUSES OF PROJECTILES.

SPECIFICATION forming part of Letters Patent No. 764,405, dated July 5, 1904.

Original application filed January 9, 1902, Serial No. 89,043. Divided and this application filed October 15, 1902. Serial No. 127,405. (No model.)

To all whom it may concern:

Be it known that I, KARL WIESER, a subject of the Emperor of Germany, and a resident of 34 Friederikenstrasse, Rüttenscheid, near Essen-on-the-Ruhr, Germany, have invented certain new and useful Improvements in Protecting-Caps for Fuses of Projectiles, of which the following is a specification.

This invention relates to a protecting-cap for fuses of projectiles, and more particularly to the class shown in my application for Patent filed January 9, 1902, Serial No. 89,043, of which this is a division. It has for its object to provide an improved cap of this kind which will be inexpensive to manufacture and can be easily applied to and removed from the fuse.

With this and other objects in view the invention consists of the parts and combinations of parts more fully hereinafter described, and pointed out in the appended claims.

In the drawings forming a part of this specification, Figure 1 is a longitudinal section of the cap, and Fig. 2 is a side view.

Like numerals indicate like parts throughout all the figures of the drawings and in the specification.

The cap A is constructed of thin sheet metal, preferably aluminium or tin-plate, having an oval shape conforming to that of the fuse. The height is such that it covers the separating-joint B between the projectile C and fuse D.

The protecting-cap is slit from the rim nearly to the apex. The wire E is soldered inside of the cap at the side of the slit and immediately above the rim and passes thence to the point where the slit in the cap begins, thence outward over the edge of the rim. Then it is directed along the line of the slit and soldered to the walls of the slit in such a manner as to close the latter. The free end of the wire is formed into a loop F. The slit could instead of being closed by soldering the wire thereto be simply soldered and then rent asunder by means of a loop secured at the side of the slit and immediately over the

rim of the cap. This construction is especially suitable for caps having walls of comparatively great strength or caps constructed of tough material.

A fastening for the cap, as well as the hermetic closure between the cap and projectile, may be accomplished in different ways; but it is preferred to place a rubber ring K in the annular groove in the shell of the projectile and secure it in this position by an internal annular rib on the cap.

In order to separate the cap from the projectile, the loop is grasped and the cap is ripped open by a pull of the wire in a direction perpendicular or nearly perpendicular to the axis of the projectile, the ripping taking place from the base of the cap toward its apex, and the separation of the cap from the projectile being simultaneous with the tearing open.

I desire it to be understood that I may make various changes in form, proportion, and minor details of construction without departing from the spirit of my invention.

What I claim is—

1. A projectile having a metallic protecting device for its fuse, comprising a cap constructed of a single piece of thin metal fitting over and secured to the outer surface of the projectile and having a suitable slit therein and suitable means closing the slit, operated to open said slit to divide the cap, and secured to the cap in a manner to remove the same from the projectile after the slit has been opened.

2. A projectile having a protecting-cap constructed with a slit, and having said slit closed by solder, and a ripping device arranged to open the slit in the cap and secured to the cap adjacent to the slit to remove the cap from the projectile after the slit has been opened.

3. A projectile having secured thereto a protecting-cap constructed with a slit that permits its opening for removal, and an opening-wire soldered to the walls of the slit and closing the same, and adapted to be torn away,

to open said slit, and being secured to the cap at its edge to remove the cap from the projectile.

4. A projectile provided with a fuse and having secured thereto, over said fuse, a protecting-cap, constructed of a single piece of thin metal, with an attaching-rim; and with a slit extending from this rim nearly to the apex, and a ripping-wire having its inner end secured to the inside of the cap to remove the cap from the projectile, and passed thence around the base of the cap and over, and soldered to the walls of the slit, for the purpose set forth.

15 5. A projectile having a metallic protecting-cap provided with a ripping-wire for ripping the cap from its rim to its apex, secured

to the cap at one end adjacent the rim and the place where the rip is to be made by the ripping-wire.

6. A projectile having a metallic protecting-cap provided with a ripping-wire for ripping the cap from its base to its apex, secured at one end to the inside of the cap, and passed around the rim of the cap adjacent the place where the rip is to be made by the ripping-wire.

The foregoing specification signed at the United States consulate at Dusseldorf, Germany, this 23d day of September, 1902.

KARL WIESER.

In presence of—

PETER LIEBER,

WILLIAM ESENWEIN.
